Primary Examiner — Sheryl Lane(74) *Attorney, Agent, or Firm* — Bruce P. LaBrie;
Resolution Legal Group(57) **CLAIM**

The ornamental design for a mounting clip as shown and described.

DESCRIPTION

FIG. 1 is a front elevation view of a mounting clip showing our new design.

FIG. 2 is a bottom view thereof;

FIG. 3 is a rear elevation view thereof;

FIG. 4 is a left side elevation view thereof;

FIG. 5 is a right side elevation view thereof;

FIG. 6 is a top view thereof;

FIG. 7 is a top perspective view thereof;

FIG. 8 is a bottom perspective view thereof;

FIG. 9 is a perspective view thereof shown adjacent to a device;

FIG. 10 is a perspective view thereof shown adjacent to a device; and,

FIG. 11 is a front elevation view thereof shown adjacent to a device.

The structural features depicted by broken lines have been shown for the purpose of illustrating environment and forms no part of the claim.
